NONREFILLABLE BOTTLE

Gerald Cahill, Chicago, Ill.

Application July 27, 1935, Serial No. 33,616

15 Claims. (Cl. 215—17)

This invention relates to a non-refillable bottle.

Many attempts have been made to provide bottles with means for making it impossible to refill them. Three methods have been employed for illicit dealers to refill a valve-protected bottle with a liquid: (1) by inserting a wire to hold the valve away from its seat; (2) by a rapid oscillating movement of the bottle while it is submerged in a liquid; and (3) by reciprocating movement with a quick return, the bottle being held in a vertical position submerged in the liquid. The first method is overcome by having a circuitous or interrupted passage between the mouth of the bottle and the valve. However, the second and third methods have been employed effectively for refilling the present types of valve-protected bottles.

A primary object of my invention is to provide a valve-protected bottle with means whereby the bottle cannot be refilled by any of the above methods. A further object is to provide means for locking the valve to its seat when either the second or third method mentioned above is used, while permitting the valve to move freely to open position when the bottle is held in a pouring position.

The invention is illustrated, in preferred embodiments, by the accompanying drawings, in which—

Figure 1 is a vertical sectional view of a bottle neck equipped with my improved means for preventing refilling; Fig. 2, a transverse sectional view, the section being taken as indicated at line 2 of Fig. 1; Fig. 3, a transverse sectional view, the section being taken as indicated at line 3 of Fig. 1; Fig. 4, a transverse sectional view, the section being taken as indicated at line 4 of Fig. 1; Fig. 5, a broken sectional view showing the bottle neck equipped with a modified form of means for preventing refilling of the bottle, the valve being shown in closed position; Fig. 6, a view similar to Fig. 5, but showing the valve raised; Fig. 7, a sectional view, the section being taken as indicated at line 7 of Fig. 8; and Fig. 8, a transverse sectional view, the section being taken as indicated at line 8 of Fig. 5.

In the illustration given in Figs. 1, 2, 3, and 4, the bottle neck A is provided with an enlargement A' near its upper end.

Received within the bottle neck A is a metal tube or casing 10 having an outwardly flared portion 11 which is expanded into interlocking engagement with the enlargement A' and for insertion within the bottle neck. In this manner, the tube 10 is permanently locked within the

bottle neck. The upper portion of the tube 10 may be spun around the upper edge of the bottle neck to form an interlock 12 and seal 12a. In the illustration given, a screw cap 13 equipped with a sealing disk 14 is clamped in position. 5 Fixed within the tube 10 is a pendulum cage 15 having its side walls interlocked with the tube 10 at the point indicated by the numeral 16. Supported by arms 17 at the upper side of cage 15 is a tubular guide 18 adapted to receive the coil-spring stem 19 of the plumb-bob 20. Fixed to the tubular guide 18 are two spaced flanges 21 which have their outer edges spaced inwardly of wall 10. An annular partition wall 22 is secured to the tube 10 and overlaps the space between the 15 flanges 21 and wall 10. By means of flanges 21 and 22, a staggered passageway is provided which prevents the introduction of a wire into the bottle to engage operating parts below the flanges. 10

As shown more clearly in Fig. 1, the lower wall 20 23 of cage 15 is provided centrally with an opening 24 through which the bob 20 may move and through which the stem 19 may oscillate.

Within cage 15 and near one side thereof is fixed a pivot 24 upon which is mounted a pendulum deflector 25. As shown more clearly in Figs. 1 and 3, the pendulum deflector is provided with a recessed end 26 adapted to receive the spring stem 19. When the pendulum deflector 25 is swung to its lowermost position, as indicated in 30 Fig. 1, it holds the bob 20 in the position indicated in dotted lines on the left hand side of the figure. In this position, the bob is locked against vertical movement. 25

Near the bottom of the tube 10 is a valve seat 35 member 27 providing a centrally disposed flow passage 28. The seat 27 is provided with an annular recess into which the metal of the tube 10 is spun at 29.

The float valve 30 of cork or other suitable 40 material is disposed above the seat 27. In the illustration given, the valve 30 is provided at its top with a metal disk 31 having an over-hanging lip or flange 32. A rod 33 extends through the valve 30 and to a point considerably below the 45 valve. Immediately below valve 30, I provide a series of thin disks 34 of cork or other suitable material to minimize friction due to expansion, which disks are separated by washers 35. In the lower portion of tube 10 is secured a closure member 36 which has inclined walls terminating in a tubular member 37 which receives and guides the lower portion of stem 33. The lower portion of tube 10 is provided with a series of apertures 50 55

- 38 through which liquid may enter the tube below opening 28.
- A ball weight 39 is secured by a flexible member 40 to the lower end of stem 33.
- 5 In the space above valve seat 27 and below pendulum cage 15 is slidably mounted a weight member 41 provided at its top with spider arms 42, as shown more clearly in Fig. 4. In order to releasably lift the valve 30 from its seat, I provide a pair of tongs 43, each one of the tongs having a free end 44 extending upwardly through openings between the spider arms. The tongs are pivotally supported below the spider arms by pivot 45 which engages depending lugs 46 carried 10 by the spider arms 42. Secured to the inner walls of the slideable weight member 41 are springs 47 which urge the depending tong arms inwardly so that the claws 48 thereof engage the flange or lip 32 of valve 30.
- 20 In the operation of the device, when it is desired to pour liquid from the bottle, it may be inverted to the usual vertical position. The weight member 41 slides toward the pendulum cage 15 while at the same time, the bob stem 19 25 slides within the tubular guide 18. As the member 41 moves toward the cage 15, the arms 44 of the tongs 43 engage the inner wall 23 of cage 15, thus spreading the tong arms 44 and causing the claws 48 to release the flange 32 of valve 30. The 30 float valve 30 is thus freed so that it may return to its seat if an attempt is made to refill the bottle. If the bottle is held in a horizontal position in an attempt to refill it, the valve return weight 39 pulls the released valve 30 to its seat.
- 35 If a rapid oscillating movement is made while the bottle is submerged, centrifugal force causes all the movable members to fly tangent to their position, and are deflected toward the mouth of the bottle, and in the action of the plumb-bob, 40 which is suspended by a flexible stem, the bob is free to fly laterally, as indicated in dotted lines in Fig. 1. In such positions, the bob is caught between the cage 15 and valve lifter member 41, and thus permits partial opening of the valve 45 only.
- If the bottle is held in a vertical position while submerged in a liquid, and given a reciprocal movement with a quick return, the movable members will tend to fly toward the mouth of the 50 bottle. The pendulum deflector 25, under such conditions, forces the stem 19 out of true alignment with the cage opening 24 and causes it to be locked in the position shown in dotted lines in Fig. 1 on the left hand side of the figure, thus 55 arresting the outward movement of the valve-lifting member 41 and thereby the opening of the valve. Thus, under any of the conditions or methods heretofore set out for refilling protected bottles, the above improved construction prevents 60 refilling the bottle.
- In the modification shown in Figs. 5 to 8, inclusive, the construction is the same as that heretofore described, except with respect to one or two features. Secured to the top of float valve 65 30 is a metal plate or disk 50 having integrally formed therewith spring fingers 51 which have inwardly turned upper ends 52. A weight-lifter member 53 is movably confined by fingers 51 so that there may be some relative movement between the valve disk 50 and the weight-lifter member 53. Integrally formed with the weight member 53 are outwardly extending lugs 54 which serve as guides or spacers. The members 54 center the weight member 53 within the tube 10. 70
- 75 As shown more clearly in Figs. 7 and 8, the weight member 53 is provided with a transverse slot 55 in which is pivotally mounted a latch 56. The locking latch 56, as shown more clearly in Fig. 7, is mounted on pivot 57 and is adapted to swing about the pivot into the locking position shown in Fig. 7. In this position, the locking latch engages plate 50 of valve 30, and thus holds the valve in partially closed position.
- Depending from the stem 33 of the valve is a metal rod 58 having a flattened end 59. A ball weight 60 is connected to the flattened end 59 by a flexible member 61.
- The lower end of the tube 10 is closed by a wall 62 which is formed to provide an annular groove 63 spaced about a centrally disposed tubular guide 64.
- In the operation of the modification shown in Figs. 5 to 8 inclusive, when the bottle neck is inverted to a vertical position as in the normal pouring position, the weight 53 slides forwardly 20 engaging the inturned ends 52 of fingers 51, thus pulling the valve 30 partially away from its seat. The ball weight 60 then strikes the flat end 59 of stem 58 and forces the remainder of the valve 25 and more particularly the valve disks 34 out of engagement with the valve passage 28, thus opening the valve. The flexible portion 61 then permits the ball 60 to fall over into the annular groove 63. In this position, the liquid flows freely 30 through the openings 38 into tube 10, and thence through valve passage 28 into the chamber thereabove and out through opening 24 in the pendulum cage, as has already been described.
- When an attempt is made to refill the bottle, the valve 30 is free to float toward its seat, it being 35 observed that the fingers 51 permit movement of the valve 30 toward its seat without disengagement from weight 53. The depending weight 60 draws at least a portion of the valve into sealing relation with the valve passage 28. It will be seen 40 that the pusher ball 60 does not prevent the return of the float valve to its seat, but on the other hand actually aids in drawing the disks 34 into the valve passage 28 when the bottle is in horizontal position.
- If the bottle is given a rapid up-and-down movement or oscillatory movement, the locking latch 56 tends to swing toward the position shown in Fig. 7, thus maintaining the valve 30 in its lower position with some of the disks 34 sealing 50 the valve opening.
- In both of the modifications illustrated in the drawings, it will be observed that pendulum means are employed on both sides of the valve, the upper pendulum means being used mainly for dogging 55 the opening of the valve and preventing the opening thereof when the bottle is held in certain positions and given certain movements. The lower pendulum serves mainly the functions of drawing the valve to its seat, locking the valve 60 in closed positions, and in the second modification, the lower pendulum has the additional function of pushing against the valve to unseat it. The double pendulums in combination with the locking means disclosed prevent the opening of 65 the valve through the employment of any of the methods heretofore discussed, and render the bottle non-refillable. In the first modification, the lower ball has a dual function, (1) returning the valve to its seat, and (2) acting as a lock in 70 the event the upper bob fails to get caught between the weight and the cage.
- While in the illustrations given, I have set forth certain specific constructions, it will be understood that such details of construction may be 75

modified greatly without departing from the principles and spirit of my invention.

The foregoing detailed description has been given for clearness of understanding only, and

5 no unnecessary limitations should be understood therefrom, but the appended claims should be construed as broadly as permissible, in view of the prior art.

I claim:

10 1. In combination with a container neck, a guard structure locked within said neck and providing a flow passage and valve seat therein, a float valve on said valve seat, weight means for positively moving said valve from its seat, and a 15 swinging member supported within said guard structure and adapted to prevent said weight means from opening said valve seat, except when said container neck is inverted to a substantially vertical position for pouring.

20 2. In combination with a bottle neck, a guard structure locked within said neck and providing a flow passage and a valve seat therein, a float valve on said valve seat, a float valve supported above said valve and releasably 25 engaging said valve, and swingable means supported by said guard structure above said valve-lifting means and adapted to be moved into obstructing position preventing upward movement of said valve-lifting means except when said container neck is inverted to substantially vertical position.

30 3. In combination with a container neck, a guard structure locked within said neck and providing a flow passage and valve seat therein, a float valve on said valve seat, a tubular guide supported at a spaced distance above said float valve, a flexible stem received within said tubular guide, a weight member secured to the lower end of said stem, said stem yielding to permit the 35 swinging of said weight member laterally into obstructing position preventing movement of said float valve away from said seat but said stem being receivable within said guide to permit movement of said float valve away from its seat when said container neck is inverted to a substantially vertical position for pouring.

40 4. In combination with a container neck, a guard structure locked within said neck and providing a flow passage and valve seat therein, a float valve on said valve seat, a float valve supported above said valve for releasably lifting said valve from its seat when the container neck is inverted, and swingable means slidably supported above said valve-lifting means for dogging the 45 movement of said valve-lifting means except when said container neck is inverted to substantially vertical position.

50 5. In combination with a container neck having a guard structure within said neck and providing a flow passage and valve seat therein, a float valve on said valve seat, a swingable member supported above said valve seat and dogging upward movement of said valve when the container is given a longitudinal reciprocal movement, and a pendulum deflector pivotally supported in said guard structure and adapted to engage said swingable member and to urge it into obstructing position when the container is given a longitudinal reciprocal movement.

55 6. In a guard structure for a bottle neck, said guard structure being provided with a valve seat and a float valve thereon, a swingable member controlling the movement of said valve from its seat, and a pendulum deflector pivotally supported at one end by said guard structure and having

its free end adapted to engage said swingable member to maintain it in valve-obstructing position when the container is given a longitudinal reciprocal movement.

7. In combination with a container neck having an enlargement therein, a guard structure locked within said enlargement and providing a flow passage and valve seat therein, a float valve on said valve seat, a float valve supported above said valve and equipped with means for releasably lifting it from its seat, a pendulum cage supported within said guard structure above said valve-lifting member, said cage providing a tubular guide, a coil wire stem received within said guide, a weight engaging the lower end of said stem, said weight being swingable into positions between said pendulum cage and said valve-lifting means to prevent upward movement of said valve-lifting means, and a weight member suspended below said valve and secured to said valve.

8. In combination with a container neck having an enlargement therein, a guard structure locked within said enlargement and providing a flow passage and valve seat therein, a float valve on said valve seat, weight means for positively moving said valve toward its seat, and automatic means for releasably lifting said valve from its seat, said valve being provided with at least one valve disk extending within and sealing the flow passage below said valve seat.

9. In combination with a flow passage and a valve seat, a float valve received on said seat, and a plurality of valve disks carried by said float valve and spaced apart by washers, said disks being received within and sealing the flow passage below said valve seat.

10. In combination with a container neck having an enlargement therein, a guard structure locked within said enlargement and providing a flow passage and valve seat therein, a float valve on said valve seat, a valve-lifting member movably mounted above said valve and equipped with tongs adapted to engage a portion of said valve, said tongs having free upwardly extending arms, and an abutment supported by said guard structure above said valve-lifting means, said abutment serving to engage said arms and to spread said tongs to release said valve when said valve-lifting member moves toward said abutment.

11. In combination with a container neck having an enlargement therein, a guard structure locked within said enlargement and providing a flow passage and valve seat therein, a float valve on said valve seat, and pendulum members supported on either side of said valve and coacting with the valve in the opening and closing thereof.

12. In combination with a container neck, a guard structure locked within said neck and providing a flow passage and valve seat therein, a float valve on said valve seat, weight means for lifting said valve from its seat, a pendulum swingably supported above said weight member and adapted to obstruct forward movement of said weight member when the bottle is given an oscillating movement and a pendulum member suspended below said valve and secured thereto, said pendulum serving to draw said valve toward its seat when the bottle neck is held in substantially horizontal position.

13. In combination with a container neck, a guard structure locked within said neck and providing a flow passage and valve seat therein, a float valve on said valve seat, weight means for lifting said valve from its seat, a pendulum

- swingably supported above said weight member and adapted to obstruct forward movement of said weight member when the bottle is given an oscillating movement and a pendulum member suspended below said valve and secured thereto, said last-mentioned pendulum being equipped with a stem by which it is adapted to push said valve from its seat when the bottle is inverted to pouring position.
- 10 14. In combination with a container neck having an enlargement therein, a guard structure locked within said enlargement and providing a flow passage and valve seat therein, a float valve on said valve seat, a weight member slidably connected to said valve and adapted to partially move said valve from its seat, a stem suspended
- 15

from said valve, and a weight flexibly connected to the end of said stem and adapted to push said valve from its seat when the bottle neck is inverted to pouring position.

15. In combination with a container neck a 5 guard structure locked within said neck and providing a flow passage and valve seat therein, a float valve on said valve seat, weight means slidably connected to said valve and adapted to lift said valve from its seat, and a locking latch piv- 10 otally connected to said weight member and adapted to engage said valve to hold said valve in partially closed position when the bottle is given an oscillating movement.

15

GERALD CAHILL.
